UNITED STATES PATENT OFFICE.

JOHN HENRY LIBBE, OF TOLEDO, OHIO.

STONE-LAYING JACK.

SPECIFICATION forming part of Letters Patent No. 362,982, dated May 17, 1887.

Application filed June 1, 1886. Serial No. 203,881. (No model.)

To all whom it may concern:

Be it known that I, JOHN HENRY LIBBE, a citizen of the United States, residing at Toledo, in the county of Lucas and State of Ohio, have 5 invented a new and useful Lifting and Carrying Stone-Laying Jack, of which the following is a specification.

My invention relates to improvements in lifting and carrying stone laying jacks which 10 are more especially adapted to moving and laying sidewalk-slab and similar stones; and the objects of my invention are, first, to provide a crane which shall have adjustments well adapted to the purpose, and second, to provide, 15 in combination with said crane, suitable hoisting and holding apparatus, all of which will be hereinafter fully explained, and will be fully illustrated in the accompanying drawings, in which—

20 Figure 1 is a side elevation on line A, Fig. 2. Fig. 2 is an end elevation on line B, Fig. 1. Fig. 3 is an enlarged side view of a locking-bolt, shown at D in Fig. 2. Fig. 4 is an end view of said locking-bolt on line C, Fig. 3. 25 Fig. 5 is an enlarged sectional view of one of the rock-lifting hooks, showing the method of attaching the same to a rock.

Similar letters refer to similar parts throughout the several views.

30 E is a horizontal bar, to which the legs F are adjustably pivoted at G.

H H are stay-bars, which are adjustably connected to the legs F and to the bar E by means of the bolts I and I'.

35 On either end of the frame shown in Fig. 1 a pair of legs, F F, are locked together by means of the cross-bars J and J', thus forming a substantial trestle for supporting the top bar, E, and its attachments. It is obvious 40 that these leg-trestles are adapted to be moved toward and from each other upon the pivots G in the direction of the arrows K. At the lower extremity of the legs F are journaled the trucks L. These trucks are adapted to roll upon the 45 tracks M and carry the mechanism which they support.

At N and N' are power-shafts having the cranks P and P'. These shafts are journaled in boxes which are attached to one of the end trestles, and are connected by multiplying gearing Q, and the shaft N' carries the winding-drum R.

At S S' S" are pulley blocks, each having a sufficient number of pulleys, so that, in combination with the gearing Q and the power-shafts 5 N and N', the desired power for lifting can be obtained. In this case the block S has one pulley, the block S' two pulleys, and the block S" has three pulleys; but I do not confine myself to the use of blocks having any definite 6 number of pulleys; but the blocks and pulleys named, in combination with the gearing and power-shafting described, are sufficient for any ordinary work required of this machine. The winding-drum R and the blocks S S' S" 6 are connected with the chains Z Z by means of a rope or chain in the ordinary manner.

At T T T are three hooks of peculiar construction. (Shown in section in Fig. 5.) These hooks are for lifting and supporting the rock 7 U, and three are required to balance the rock 7 in a level position. In Fig. 5 the form of these hooks is shown as they appear when cut on line b, Fig. 2. The upper extremity, V, of this hook (where the lifting-chain Z attaches) 7 and the lower extremity, W, (which lies under the rock U,) both lie substantially in the same gravity-line, X, with the exception that the extremity W should project slightly beyond the said line, as shown in the drawings, 80 the purpose of which is to prevent the said hook from slipping from its hold.

The locking-bolt shown in Figs. 3 and 4 is intended to slide in either direction, as indicated by the double-headed arrow in the drawings, 85 and its use is to lock or release the crank Y.

The operation of this mechanism is as follows: The tracks M M having been located a sufficient distance apart to readily admit the 90 breadth of the stone which is to be operated upon, the trestle-legs F F are adjusted to correspond to the said breadth by being swung upon the pivots G, and secured in position by means of the stay-bars H H. The hook on the 95 pulley-block S" is connected with the hooks T T T by means of ordinary chains, Z, three of said hooks T T T being required to properly balance the rock U, as before mentioned. The rock is now suspended by turning the crank P or P' in the usual manner, the crank P or the crank P' being used, according to the weight of the rock to be suspended. When the said rock has been raised a sufficient height,

the end D' of the bolt D is passed beyond the revolving plane of the vertical arm of the crank, thus preventing the further revolving of the crank. This is shown in Figs. 2 and 3. By this means the rock is held suspended any length of time, for the purpose of moving the said rock any distance over the tracks M M, within the limit of their lengths,) and then deposited in the desired position in an obvious manner. To prevent the winding apparatus being tampered with when not in use, the bolt D may be placed in the position shown in Fig. 3, and by means of any suitable lock secured to the crank P or P'.

Having described my invention, I do not claim, broadly, a lifting jack of any of the forms in general use; but

What I do claim as new, and desire to secure by Letters Patent, is—

1. A stone-laying jack comprising the bar E, the trestle-legs F F, the trucks L, the connecting cross-bars J and J', the stay-bars H H, and the bolts I I', the said legs F F being pivotally attached to the sides of the bar E and

adapted to be swung upon their pivots and to 25 be secured in fixed position by means of the said stay-bars H H and bolts I I and I' I', said jack being adapted to be rolled upon tracks M M, all combined substantially as shown, and for the purpose specified.

2. In a stone-laying jack, the combination of the bar E, trestle-legs F F, stay-bars H H, power-shafts N N, pulley-blocks, and the chains Z Z, provided with the hooks, all substantially as shown and described.

3. A stone-laying jack consisting of the bar E, the legs F F, pivotally attached thereto and adapted to swing therefrom, the stay-bars H H, pivotally connected to the legs and adjustably secured to the bar, the hoisting-drum, 40 means for operating the same, and the locking-bar D, all combined to operate substantially as and for the purpose set forth.

JOHN HENRY LIBRE.
